UNITED STATES PATENT OFFICE

WINTHROP K. HOWE, OF ROCHESTER, NEW YORK, ASSIGNOR TO GENERAL RAILWAY SIGNAL COMPANY, OF ROCHESTER, NEW YORK

CAR RETARDER FOR RAILROADS

Application filed December 30, 1929. Serial No. 417,439.

This invention relates to car retarders of the type in which brake shoes along the track engage the sides of the car wheels, and more particularly to the motive power means for operating such brake shoes.

In my prior application Ser. No. 244,259, filed January 3, 1928, I have disclosed a car retarder, in which if a certain member is operated to its active position it will, through the medium of springs, cause braking pressures to be applied to the various brake shoes, these pressures being dependent upon the position of such member. Fluid pressure means, and particularly an arrangement where a liquid is used as the fluid, has been found to lend itself especially well, where an ordinary force is converted into a much larger force, and where such force is maintained for an appreciable period of time. Also, liquid fluid operated means is particularly well applicable where a certain device is to be moved to a particular position rather than where such device is to exert a predetermined pressure, in the latter case of which a gaseous fluid would preferably be used. In view of the foregoing and other important considerations, it is proposed, in accordance with the present invention, to operate a car retarder of the type shown in my prior application by liquid fluid pressure means, conveniently called hydraulic means, and to control such apparatus from a remote point in such a manner that the member of the car retarder may be operated to a predetermined position irrespective of the forces necessary to cause it to assume such a position.

Other objects, purposes and characteristic features of the present invention will be in part understood from the accompanying drawing and will in part be more particularly described hereinafter.

In describing the invention in detail, reference will be made to the accompanying drawing, in which:

Fig. 1 illustrates a plan view of a car retarder, together with the fluid pressure means for operating such car retarder, the pressure tank, the operating cylinder, its associated valves and the contact operating cam of which are shown in cross section; and,

Fig. 2 shows an end elevation, partly in section, of the car retarder shown in Fig. 1.

Retarder apparatus.—Referring particularly to Fig. 2, the ties 2 of the railway track carry the usual track rails 15, which have arranged on opposite sides thereof brake beams 12, containing brake shoes 26, these brake beams 12 being operated by levers 16 and 18 through the medium of cross bars 11 and springs 21. The cross bars 11, on the other hand, are operated by angle levers 49 through the medium of the longitudinal movable member 50. This member 50 is operated through the medium of multiplying lever 72, the rod 68 and the angle lever 61, this angle lever 61 offering a variable lever ratio which increases as the retarder is closed. The parts just described have been more fully described in my prior application above mentioned, to which reference may be had if desired.

Hydraulic apparatus.—The angle lever 61, as shown, is operated by the cross head 70, through the medium of the pitman rod 60. It will be noted that the angle lever 61 has its fixed and movable pivots so arranged, that the compression force in rod 68 increases, as compared with the force exerted by the rod 60, as the brake shoes are moved toward each other. This expedient is adopted so that the force exerted by the piston 75 is greatly multiplied for those positions of the car retarder in which the larger forces are required. This cross head 70 is slidably mounted in guide members 71, and is operated through the medium of the piston rod 73 connected to the piston 75. Fluid pressure may be caused to flow from the pressure tank PT to either side depending upon the position of the cut-off valve 76, this cut-off valve 76 being normally held in its middle position by the springs 78 and 79, and being operable to one extreme position by the solenoid 80 and to the other extreme position by the solenoid 81, these solenoids acting on armatures 82 and 83, respectively. The pressure tank PT includes a piston 84 and a weight 85, this piston and weight exerting a predetermined and fixed force upon the liquid, and assuming a position depending upon the amount of liquid that has been 100

forced into the pressure tank PT through the medium of the pump P operated by a motor M. The valve 76 is used, not only to allow fluid pressure to flow into the cylinder 74, but 5 also conducts liquid from this cylinder 74 back through the pipe 77 into the storage tank ST, the pump P, of course, again pumping the liquid from the storage tank ST into the pressure tank PT, making it again available for operating the piston 75.

The present apparatus also includes control mechanism for controlling the solenoids 80 and 81. Although, any suitable circuit arrangement may be used for operating the solenoids 80 and 81, this apparatus preferably includes means for operating the piston 75 to a predetermined position and then discontinuing movement of this piston 75. In the particular arrangement shown the cross head 70 operates a slide cam 90 through the medium of a suitable multiplying lever, such as the lever 91, and including the connecting rod 92. This slide cam 90 has three cam surfaces 93, 94 and 95 which are arranged 10 in different vertical planes, the roller 96 co-operating with the cam surface 93, the roller 97 co-operated with the cam surface 94 and the roller 98 co-operated with cam surface 95. These rollers 96, 97 and 98 operate respectively the contacts 100, 101 and 102. It will be noted that the contact 100 is included in the circuit leading to the solenoid 81 and that the contact 102 is included in a circuit leading to the solenoid 80, and that the contact 101 in the intermediate position of the retarder shown does not engage either of its stationary contacts. These cam surfaces 93, 94 and 95, and the rollers 96, 97 and 98 are so related that only one of these contacts 100, 15 101 or 102 are operated at one time. Any one of the contacts 100, 101 or 102 may be connected to the positive side of the battery 105 through the medium of the lever 106. In practice, this lever 106 is located in a tower, possibly a very considerable distance 20 from the car retarder, in which tower there are located the levers of all of the various car retarders of that particular classification system, this tower having been conventionally represented by the dotted rectangle T. It is believed that the invention will be better understood by briefly considering the 25 operation of the apparatus.

Operation.—Attention is directed to the fact that the apparatus as shown in the drawing is in its intermediate position, in which position a passing car would be braked to a medium extent. Let us now observe how the brake shoes 26 may be operated to their 30 full braking position. In order to effect maximum braking, the operator will operate his lever 106 to the extreme right hand position, and in so doing will effect energization of the solenoid 80 through the following circuit:—beginning at the positive side of the

battery 105, wire 104, lever 106, wire 107, contact 102, wires 108, 109 and 110, solenoid 80, wires 111 and 112, back to the negative terminal of the battery 105. Completion of this circuit causes the solenoid 80—82 to move 70 the slide valve 76 toward the right, thereby allowing fluid pressure to flow from the pressure tank PT through the pipe 113, through the port 114, to the chamber to the left of the piston 75. This flow of fluid pressure causes the piston 75 to be operated toward the right, thereby moving the brake shoes 26 toward each other, and operating the contact 101 to its upper position through the medium of the roller 97 and cam surface 75 94. As movement of this contact 101 to its upper position has been completed, the contact 102 will move away from its back stationary contact, thereby opening the circuit for the solenoid 80—82 and causing the piston 75 to remain in its then operated position, in which position the car retarder assumes its maximum braking position.

Let us now observe how the car retarder may be operated to its full open or non-braking position. In order to accomplish this the operator will move his lever 106 to the extreme left hand position, thereby completing the following circuit for the solenoid 81—83:—beginning at the battery 105, wire 104, lever 106, wire 115, contact 100, wires 116, 117 and 118, coil 81 of the solenoid 81—83, wires 119 and 112, back to the battery 105. Completion of the circuit just traced will effect operation of the slide valve 76 to its extreme left hand position, thereby conducting fluid pressure from the left side of the piston 75 back to the storage tank ST through the medium of pipe 77, and likewise connecting the right hand side of the piston 75 to the pressure tank PT through the medium of the pipe 113, so that the piston 75 will be moved toward the left, effecting separation of the brake shoes 26. Movement of the piston 75 toward the left will cause the contacts 101 and 100 to be operated in the order given, the contact 102 already being down and 101 assuming its lowermost position before the movement of the contact 100 is started. Downward movement of the contact 100 causes the circuit for the solenoid 81—83 to be broken, thereby closing the port 120 in the slide valve 76 and causing the piston 75 to remain in its then operated position. Although any suitable pressure fluid may be used, in accordance with the present invention this pressure fluid is preferably of the liquid non-compressible type, such as oil, glycerine, anti-freeze water solution, or the like.

Consider now, a movement of arm 106 to its intermediate position (as shown in full lines). Positive energy from battery 105 is placed on contact 101, which is now in its lower position, to thus energize solenoid 80

through a circuit obvious from the drawing, to move valve 76 to the right, to cause fluid pressure to move piston 75 to the right and thus position the brake shoes nearer to the 5 running rails, until cam 94 operates on 97 to raise contact 101 and de-energize 80. The parts are then held in the intermediate, or shown, position, until there is another operation of lever 106.

10 A car retarder has thus been provided, which may be operated by fluid pressure, and in which the fluid pressure is automatically controlled in accordance with the position assumed by the main operating member of such 15 car retarder, and further flow of fluid pressure is cut-off when the retarder has assumed such position. Also, a fluid pressure operated retarder has been devised in which the pressure exerted upon the retarder is variable 20 in spite of the application of constant fluid pressure.

Having thus shown and described one rather specific embodiment of the present invention, it is desired to be understood that 25 the particular embodiment illustrated has been selected for the purpose of disclosing the principles and operating characteristics of the invention rather than its scope or the exact construction preferably employed in 30 practicing the same, and that various changes, modifications and additions may be made to adapt the invention to the particular problem encountered in practicing the same, all without departing from the spirit or 35 scope of the invention or the idea of means underlying the same, except as demanded by the scope of the following claims.

What I claim as new is:—

1. In a car retarder, the combination with 40 a railway track, brake shoes on opposite sides of each track rail, springs associated with said brake shoes, a member for operating said brake shoes through the medium of said springs, a piston for operating said member, 45 a liquid fluid source of pressure, an electrically operated valve for applying fluid pressure to either side of said piston, a circuit for controlling said valve including a manually operable controller, and other means 50 in said circuit for operating said valve to its inactive position when said member has been operated to a predetermined position.

2. In a car retarder, the combination with 55 a railway track, brake shoes on opposite sides of each track rail, springs associated with said brake shoes, a member for operating said brake shoes through the medium of said springs, a variable multiplying lever for operating said member, hydraulic means for operating 60 said lever, a controller operated by movement of said member and including a plurality of cam operated contactors, and a circuit for controlling said hydraulic means including said controller for stopping movement of said hydraulic means by opening a

said contactor, when said member has been moved to a predetermined position.

3. In a car retarder, the combination with a railway track, brake shoes on opposite sides of each track rail, springs associated with 70 said brake shoes, a member for operating said brake shoes through the medium of said springs, a variable multiplying lever for operating said member, hydraulic means for operating said lever from a source of fluid pressure, a controller operated by movement of said member, and a circuit for controlling said hydraulic means including said controller for stopping movement of said hydraulic means when said member has been 75 moved to a predetermined position.

4. In a car retarder, the combination with a railway track, of brake shoes on opposite sides of each track rail, springs associated with said brake shoes, a member for operating said brake shoes through the medium of said springs, a piston for operating said member, a source of fluid pressure, an electrically operated valve for applying fluid pressure to either side of said piston, a circuit for controlling said valve including a manually operable controller having a plurality of separate operative positions, and other means, including a cam operated contactor corresponding to each said operative 90 positions, included in said circuit for operating said valve to its inactive position when said member has been operated to a predetermined position.

5. In a car retarder, the combination with 100 a railway track, of brake shoes on opposite sides of each track rail, springs associated with said brake shoes, a member for operating said brake shoes through the medium of said springs, a piston for operating said member, 105 a source of fluid pressure, an electrically operated valve for applying fluid pressure to either side of said piston, a circuit for controlling said valve including a manually operable controller having a plurality of separate operative positions, and other means, including a cam operated contactor corresponding to each said operative positions, included in said circuit, for making and breaking 110 said circuit, for operating said valve to 115 its inactive position when said member has been operated to a predetermined position.

In testimony whereof I affix my signature.

WINTHROP K. HOWE.
